PERCUSSIVE DRILL.

Specification of Letters Patent. Patented Apr. 14, 1914.

1,093,266.

Application filed May 31, 1912. Serial No. 700,635.

To all whom it may concern:

Be it known that I, CHARLES C. HANSEN, a citizen of the United States, residing in Easton, in the county of Northampton and 5 State of Pennsylvania, have invented certain new and useful Improvements in Percussive Drills, of which the following is a specification.

This invention relates to percussive drills 10 and more particularly to a front head and buffer construction for drills of the type shown as for instance in patents to Leyner, Nos. 651,487, 709,022 and 739,551. In drills of this type the forward stroke of the piston is not cushioned by the operating fluid and under normal drilling conditions the piston is kept from hitting the front of the cylinder because it first strikes the drill steel which is in contact with the work. 15 Under some conditions however the piston is reciprocated when the steel is not in contact with the work, as when the drill is being cranked back out of a hole. In such a case the piston hits the front end of the cylinder with considerable force. In drills heretofore used this impact of the piston on 20 the front of the cylinder has been cushioned by a stationary heavy ring of rubber, which has proved unsatisfactory for several reasons, and also by slidably mounting the whole front part of the tool in the cylinder 25 and securing it resiliently by springs on the outside of the cylinder. This has proved unsatisfactory also as the inertia of the front head and steel holding means is considerable and the shock is destructive not only to the front end of the piston but to the part 30 directly receiving the blow.

The object of the present invention is to 35 provide a means whereby the rubber ring can be eliminated and the disadvantages of the spring construction largely obviated. With this object in view I have devised a construction a practical embodiment of which 40 is shown in the accompanying drawings in which:

Figure 1 shows a plan of the drill partly in section showing the piston at the extreme forward end of its stroke. Fig. 2 shows a 45 vertical longitudinal section on the line II-II of Fig. 1 showing the piston part way on its back stroke.

The drill as shown comprises the cylinder

1 in which reciprocates a piston 2, the movement of which is controlled by a valve 3 of 55 any desired construction. The forward end of the piston consists of a fluted bar which is of smaller diameter than the main portion of the piston leaving a shoulder 4 against which the operating fluid acts. For- 60 ward of the cylinder proper the interior of the cylinder casing 1 is increased in diameter leaving a shoulder against which abuts a metal buffer or packing ring 5. In the front of this and slightly separated from it ex- 65 cept at the end of the forward stroke of the piston is a sleeve 6 provided with a flange 7 which is in sliding contact with the inner surface of the cylinder casing 1. Between the ring 5 and the flange 7 is a helical spring 70 8 which tends to keep these parts separated as shown in Fig. 2. In front of the flange 7 and contacting with it is a sleeve 9 which can move longitudinally in the cylinder cas- 75 ing 1 but is prevented from rotary move- ment by the pin 10 engaging the flange 11 which abuts the forward end of the cylinder casing 1.

Rotatably mounted in the sleeve 9 is a tool sleeve 12 which is provided with a chuck 13 80 into which fits the back end of the drill steel 14. Abutting against the forward end of tool sleeve 12 is a drill steel retaining ring 15 over which fits the front head cap 16 through which pass bolts 17. Between the 85 heads 18 of bolts 17 and the front head cap 16 are springs 19 which serve to hold the cap piece 16 and the flange 11 of sleeve 9 resili- 90 ently against the front end of the cylinder casing 1.

In the operation of the drill of the shoul- 95 der 4 of the piston strikes the ring 5 it will move it forward slightly against the cushioning pressure of the spring 8 which is sufficiently strong to give the sleeve and hence the entire forward part of the drill a slight start forward before the ring 5 con- 100 tact with the rear end of sleeve 6. After this contact is made the further movement of the piston will cause the positive move- except cylinder casing 1 against the cushioning pressure of the springs 19 until the parts take the position shown in Fig. 1 with the flange 11 slightly separated from 10 the front end of the cylinder casing 1. In

this way the impact of the piston on the forward part of the drill is taken up gradually and without excessive shock.

It is to be understood that the device as shown and described discloses only one modification of my drill and other changes and modified forms are included within the spirit and scope of my invention as expressed in the claims.

10. What I claim is:

1. In a percussive drill, a cylinder, its piston, a buffer for said piston, drill steel holding means, said buffer and drill steel holding means being longitudinally movable in said cylinder by the forward movement of said piston, and said buffer being so positioned as to contact with said drill steel holding means after slight forward movement, resilient means opposing the forward movement of said buffer, and further resilient means opposing the forward movement of said drill steel holding means.
2. In a percussive drill, a cylinder, its piston, a buffer for said piston, drill steel holding means, a sleeve forward of said buffer and engaging said drill steel holding means, said buffer, steel holding means, and sleeve being movable longitudinally of said cylinder, a spring yieldably holding said sleeve slightly separated from said buffer,

and resilient means yieldably holding said steel holding means against forward movement.

3. In a percussive drill, a cylinder, its piston, a resiliently held buffer against which said piston contacts near the forward end of its stroke, movable drill steel holding means forward of said buffer, positioned to be engaged by said buffer after slight movement of said buffer, and resilient means opposing forward movement of said drill steel holding means.

4. In a percussive drill, a cylinder, its piston, a resiliently held buffer against which said piston contacts near the forward end of its stroke, movable drill steel holding means forward of said buffer, positioned to be engaged by said buffer after slight movement of said buffer, a front head cap engaging the forward end of said steel holding means, and movable longitudinally of said cylinder, bolts through said cap, and springs on said bolts for resiliently holding said cap and said steel holding means against forward movement.

CHARLES C. HANSEN.
